(57) **CLAIM**

The ornamental design for a arm rest for medical scanner as shown and described.

DESCRIPTION

FIG. 1 is a front elevational view showing an arm rest for medical scanner according to our novel design;

FIG. 2 is a rear view elevational view thereof;

FIG. 3 is a mapping of FIG. 2 for the enlarged partial views shown in FIGS. 3A-3D;

FIGS. 3A-3D are corresponding enlarged partial views thereof;

FIG. 4 is a left elevational view thereof;

FIG. 5 is a mapping of FIG. 4 for the enlarged partial views shown in FIGS. 5A-5D;

FIGS. 5A-5D are corresponding enlarged partial views thereof;

FIG. 6 is a right side elevational view thereof;

FIG. 7 is a mapping of FIG. 6 for the enlarged partial views shown in FIGS. 7A-7D;

FIGS. 7A-7D are corresponding enlarged partial views thereof;

FIG. 8 is a top plan view thereof;

FIG. 9 is a bottom plan view thereof;

FIG. 10 is a mapping of FIG. 9 for the enlarged partial views shown in FIGS. 10A-10H; and,

FIGS. 10A-10H are corresponding enlarged partial views of FIG. 10.

The broken lines forms no part of the claimed design. The short-dash long-dash lines are the partial view boundary indicators and form no part of the claimed design.

1 Claim, 30 Drawing Sheets
